UNITED STATES PATENT OFFICE.

JOHN E. AHLVIN, OF JOLIET, ILLINOIS.

JAMB FASTENING.

Application filed June 12, 1919. Serial No. 303,682.

To all whom it may concern:

Be it known that I, JOHN E. AHLVIN, a citizen of the United States, residing at Joliet, in the county of Will and State of Illinois, have invented a new and useful Jamb Fastening, of which the following is a specification.

This invention relates to means for attaching door-frames, window-frames and the like to the studding or wall of a building; and the primary object is to provide a simple construction whereby the jamb or frame member may be readily and securely attached to the wall or framing of the building, the invention facilitating the work of squaring the window-frame, or door-frame, as the case may be.

The invention is illustrated in its preferred embodiment in the accompanying drawing, in which—

Fig. 1 represents a plan view of an improved jamb-fastening device employed; Fig. 2, an edge elevational view of the same; Fig. 3, a horizontal sectional view of the vertical member of a door-jamb or frame with the improved attachment secured thereto; Fig. 4, a broken horizontal sectional view showing the frame of a wall and a vertical jamb or frame member secured thereto by means of the improved fastening device; and Figs. 5, 6, and 7, views showing a modification.

In the construction illustrated, A represents the studding or wall of a building; B, a jamb or frame set in an opening in the wall; and C, my improved jamb-attaching device.

It will be understood that a plurality of the fastening devices C may be employed for securing each vertical jamb member B to the wall. Ordinarily, three or four of the fastening members C will suffice to secure an ordinary door-jamb in position, preparatory to applying the trim.

The improved fastening device C preferably comprises a sheet-metal strip 1, which ordinarily is about eight inches in length. This thin metal bar has each lateral edge provided with a series of teeth or brads 2, 3, and 4, which are formed by shearing the metal at the lateral edges of the member along diagonal lines and bending the metal at right angles to the member 1, thus forming pointed teeth. The teeth 2 and 4 are spaced the same distance from the ends of the member 1; and the end-portions

1^a of the member 1 are provided near their attached ends, or base-portions, with hook-shaped members 5, each having a shank 5^a forming an acute angle with the plane of the member 1, and a pointed extremity 5^b forming substantially a right-angle with the shank 5^a. The members 5 are thus hook-shaped members having their pointed portions directed towards each other somewhat, as indicated in Fig. 2, that is, the hooks are bent away from the extremities of the member 1. Said hooks may be formed by shearing the metal of the end-portions 1^a of the bar along convergent lines, so as to cut out a portion of the metal at an intermediate point, except for the base-end, which is left unsheared, the metal being struck or forced from the plane of the member 1 and bent to form hooks.

The ends 1^a of the member 1 are provided with perforations 6, adapted to receive nails.

In the use of the improved fastening device, for the purpose of setting a door-frame in its opening and enabling the door-frame to be readily squared and attached, a number of the devices C are first secured to the back-side of the jamb member B, the fastening members C being located at different heights. Ordinarily, three of the members C will suffice for a door of ordinary height. The brads 2, 3 and 4 are driven into the rear-side of the member B, and the point-portions 5^b of the members 5 are driven into the edges of the member B. The angular brads 5^b may be driven into the edges of the board B by hammering upon the elbow-portions of the brads. After a number of the fasteners C have been applied to each vertical board B of the door-frame, the door-frame is set in place in the door-opening, and the projecting end-portions 1^a are bent at right angles to the body of the bar and away from the jamb B, so as to embrace the wall A. The ends of the fastening-member are then secured to the wall by means of nails 7 which pass through the openings 6. After the fastening member is secured both to the door-frame and to the wall, it constitutes, in effect, a U-shaped bracket connecting the door-frame to the wall, the web-portion of the U-shaped bracket having the integral securing-brads which enter the frame member B at its rear side and lateral edges. The face-plates of the jamb, or the trim, may be applied after the door-

110

frame has been secured in its opening. The metal fastening members thus reinforce the ordinary trim in securing the jamb members B to the wall.

- 5 It may be observed that inasmuch as the fastening members may be secured to the jamb member B before the door-frame is inserted in the wall-opening, it is a very easy matter, after the end-portions 1^a have been 10 bent so as to embrace the wall, to drive the nails 7 as the operation of squaring the door-frame proceeds. Thus, with the improved fastening device, a workman may easily set a door-frame, or a window-frame, square the 15 frame and secure it in position, preparatory to applying the wall-trim.

If desired, the jamb-fastener may be formed in two parts, and applied as shown in Fig. 7. Thus, C' and C² represent the 20 two parts, or members in this modification. The two parts are similar and complementary, each being of somewhat less than half of the length of the member C. The member C' is shown in plan and edge elevation in 25 Figs. 5 and 6, respectively. Each of said members is provided with attaching prongs which are numbered the same as the corresponding parts of the member C. In this case, however, each of the members C' and C² is provided with brads or prongs 3 which correspond with the brads 3 of the member C. The body portions of the members are provided with perforations 8, which may receive nails, or screws, 9. This two-part fastener is adapted to walls of varying thickness.

The foregoing detailed description has been given for clearness of understanding only, and no unnecessary limitation should be understood therefrom.

40 What I regard as new and desire to secure by Letters Patent is:

1. A fastening device for the purpose set

forth comprising a sheet metal bar equipped with an integrally formed brad projecting 45 at right angles to the bar, and equipped also with an elbow-form brad integral with the bar, said bar having an extremity projecting beyond said elbow-form brad and adapted for attachment to a wall, said extremity 50 being disposed substantially at right angles to the body of said bar, and said elbow-form brad being located at the junction of the body of the bar with the bent extremity.

2. Fastening means for the purpose set 55 forth, comprising sheet-metal bar-portions equipped with integrally formed brads projecting substantially at right-angles to the bar-portions and provided also with elbow-form brads formed integrally with the bar- 60 portions, said bar-portions having extremities projecting beyond said elbow-form brads and adapted to be secured to a wall.

3. Fastening means for the purpose set 65 forth, comprising sheet-metal strip-portions having lateral edge-portions sheared and the metal bent at right-angles to the strip-portions to form brads, said strip-portions having also elbow-form brads positioned intermediately between the lateral edges of the 70 strip-portions and some distance from the extremities, said elbow-form brads being formed by punching the metal through and the extremities of the strip-portions being 75 provided with nail-receiving perforations.

4. A fastening device for the purpose set 80 forth, comprising a sheet metal member equipped with integrally formed brads projecting at substantially right angles to said member and provided also with an elbow- form brad formed integrally with the sheet metal member, said sheet metal member having an extremity projecting beyond said elbow-form brad and adapted to be secured to a wall.

JOHN E. AHLVIN.
